UNITED STATES PATENT OFFICE.

ALFRED CHARLES KERRISON, OF ST. JOHN, NEW BRUNSWICK, CANADA.

RAIL-JOINT.

No. 858,659.

Specification of Letters Patent.

Patented July 2, 1907.

Application filed March 2, 1907, Serial No. 360,167.

To all whom it may concern:

Be it known that I, ALFRED CHARLES KERRISON, a subject of the King of Great Britain, and a resident of 30 Summer street, in the city of St. John, in the Province of New Brunswick, in the Dominion of Canada, have invented certain new and useful Improvements in Rail-Joints, of which the following is a specification.

My invention relates to improvements in rail joints, and the object of the invention is to dispense entirely with the use of fish plates and the necessary bolts and lock nuts or other means of joining the rails in a line of rails, and it consists essentially of the novel arrangement and construction whereby a rail having a tongue at one end and a corresponding groove at the other is joined to the next rail in the line by the introduction of the said tongue into the groove of the said next rail, the various parts of the construction being herein-after set forth in detail and shown in the accompanying drawings that form part of this specification.

20 In the drawings, Figure 1 is an elevation of a line of two rails broken away intermediate of the length of each rail and showing the rail joint. Fig. 2 is a perspective detail of the end of the rail showing the groove. Fig. 3 is a perspective detail of the end of the rail showing the tongue. Fig. 4 is a horizontal section showing a plan of the arrangement of the tongue and groove.

Referring to the drawings, 1 and 2 are rails each of said rails having at one end its base 3 projecting longitudinally beyond its head 4. 30 5 is a lateral wall formed at the terminus of the head 4 and extending downwardly across the end of the web 6 to the base 3.

7 is a groove closed by the walls 8 and 9 extending outwardly from the wall 5 to the end of the base 3 and 35 having the vertical slot 10 through the end wall 11 thereof. The walls 8 and 9 extend upwardly from the base to a level immediately below the body of the head 4. The other end 12 of each rail has the head 4 extending beyond the base 3 for a distance corresponding to the 40 extension of the base beyond the head at the grooved end.

13 is a wall similar to the wall 5 and extending downwardly from the head 4 to the base 3 and across the end of the web 6. 14 is a tongue extending downwardly 45 from the body of the head 4 and terminating on a level with the upper surface of the base 3, the tongue 14 being joined to the wall 13 by the neck 15. 16 are spikes securing the rails 1 and 2 to the sleepers 17 as customary.

It will readily be seen in this invention that on introducing the tongue 14 into the groove 7, the neck 15 fitting into the slot 10, the locking of the rails 1 and 2 is complete as both rails are firmly secured to the sleepers by the spikes 16 and the bottom of the tongue 14

rests on the base 3. As illustrated in Fig. 4 the tongue 14 does not completely fill the groove 7 but has a clearance space at the front and back thereof, and the neck 15 is slightly longer than the slot 10 to accommodate the expansion and contraction of the rails when laid in a line. The tongue and groove arrangement as herein described practically forms a chair for the rails and consequently there will be no strain when a great weight 55 passes thereover and the pounding of the vehicle wheels at the rail joints is minimized, particularly as the sides of the body of the head 4 rest on the top of the walls 8 and 9 and the side surfaces will abut against one another 60 joining the rails in such a manner that they may be said almost to be integral.

The tongue 14 is here shown as rectangular in shape and the groove corresponding to said tongue, but it must be understood that the said tongue and groove 70 may be made in any suitable shape and form, and further a slot is shown in the end wall 11, whereas another arrangement of slot or slots may be made.

The advantages of this invention are particularly in the elimination of the fish plates now used for joining 75 rails thereby reducing the liability of accidents to the railway vehicles passing along lines of rails and the great saving in labor in the laying of the rails and in the maintenance of the same.

The description herein points more directly to the 80 use of this form of joint for railway lines but it must be understood that the invention may be applied in making joints in other rails such as banister rails.

What I claim as my invention is:

1. In a rail joint, a rail having at one end a box formed 85 on top of its base beyond the head thereof, said box having a vertical slot in its end wall, and at the other end having unbroken cross head formed at the extreme end of an extension beyond the base from the web, said cross head and said extension projecting downwardly from the 90 head and from the end of said base, a vertical wall extending upwardly to said head, said cross head forming a tongue adapted to fit in a box similar to the aforesaid box and abut against said vertical wall, substantially as described.

2. In a rail joint, a rail having an enlarged portion to 95 its web at one end thereof and vertical grooves extending upwardly to the head of the rail from the lower edge of said enlarged portions and the base of said rail terminating at said grooves, and a rail having its web 100 spreading to each side on said base forward of the head and converging at the terminating to form a jaw adapted to grip the aforesaid rail in the said vertical grooves, substantially as described.

Signed at the city of St. John, in the Province of New 105 Brunswick, in the Dominion of Canada, this 20th day of February, 1907.

ALFRED CHARLES KERRISON.
